DESIGN FOR AN EMBROIDERED FABRIC

Frank Nicrosini, Bayside, Long Island, N. Y.

Application December 22, 1937, Serial No. 73,795

Term of patent 3½ years

To all whom it may concern:

Be it known that I, Frank Nicrosini, a citizen of the United States, residing in the city of Bayside, Long Island, in the State of New York, have invented a new, original, and ornamental Design for an Embroidered Fabric, of which the following is a specification, reference being had to the accompanying drawing forming a part thereof.

The figure on the drawing is a plan view of an embroidered fabric showing my new design.

I claim:

The ornamental design for an embroidered fabric as shown.

FRANK NICROSINI.
